UNITED STATES PATENT OFFICE.

JOHN BACHMANN, OF CHICAGO, ILLINOIS.

TOBACCO PIPE.

Application filed November 1, 1923. Serial No. 672,170.

To all whom it may concern:

Be it known that I, JOHN BACHMANN, a citizen of the United States, residing at Chicago, in the county of Cook and State 5 of Illinois, have invented certain new and useful Improvements in Tobacco Pipes, of which the following is a description.

My invention relates to that general class of devices known as tobacco pipes, and more 10 particularly to improvements for normally closing the end of the draft passage therethrough, said closure being removable so as to permit the easy cleaning of said passage when desired.

15 My invention has among its objects the production of a device of the kind described, which is simple, convenient, efficient and satisfactory for use wherever found applicable.

20 Many other objects and advantages of the construction herein shown and described will be obvious to those skilled in the art from the disclosures herein given.

To this end my invention consists in the 25 novel construction, arrangement and combination of parts herein shown and described, and more particularly pointed out in the claims.

In the drawings, wherein like reference 30 characters indicate like or corresponding parts:

Fig. 1 is a perspective view of my device;

Fig. 2 is a sectional view of the same;

35 Fig. 3 is an enlarged fragmentary section showing the end closure for the draft passage; and

Fig. 4 is a sectional view taken substantially on line 4—4 of Fig. 3.

In the drawings, wherein I have illustrated the preferred embodiments of my invention, there is shown a pipe having a chambered bowl portion 1 with a stem 2 extending therefrom. The stem may be made in one or more parts, there being two parts 45 shown, and may be either integral with or separate from the bowl.

Extending clear through the stem and the bowl is a draft passage 3, this draft passage being continuous from the free end of the stem to the exterior of the bowl, and preferably being arranged so that it includes the lower portion of the tobacco chamber. The passage from the stem to the tobacco chamber is always open when the pipe is in 55 use and I have arranged a closure at the end of the passage through the bowl.

This closure preferably comprises a cup-shaped member having an annular rim 4, a hub or seat 5 having a tapered exterior peripheral wall 6, a web 7 connecting the hub and rim at one side of the rim, and an annular outwardly directed flange 8 at the other end of the rim. Slits 9 may be formed through the rim at the flanged end, if desired, so as to render the rim slightly 65 expandable thereat. The hub is provided with a bore 10 therethrough of the same size as the passage-way 3 and in registry therewith.

A plug or cap having a head 11 is provided with a chamber 12 from one end so as to form a neck portion 13 adapted to frictionally enter the open end of the cup-shaped member and form a closure therefor. A gasket or disk 14 is arranged in the 75 chamber 12, the free end of the neck portion 13 being flanged or peened radially inwardly as at 15 to prevent the gasket from falling out. A spring or other resilient member 16 is interposed between the gasket 80 and the bottom wall of the recess 12 to constantly urge the gasket outwardly of the recess and against the hub or seat 5 so as to form an effective seal for the draft passage. The cup-shaped member is pressed into the 85 bowl at the end of the draft passage and may be cemented thereat if desired, the cap being removably insertable thereinto.

Thus it is seen that I have provided an effective closure for the end of the draft 90 passage and which will be efficient in operation, will not become easily lost or injured, and which will be relatively inconspicuous when in place.

The stem 2 may be either straight or bent 95 and in both cases the operation of the device will be the same. When it is desired to clean the passage, the cap is removed either by the finger or by any suitable tool, such as a knife, a coin or the like, and a pipe cleaner is inserted through the stem and finally drawn outwardly of the passage from the closure end. Thus there is no danger of the nicotine being drawn up into the mouthpiece 100 when removing the cleaner. The closure may be fitted to either old pipes or new ones, as desired. It will be noted that I so form the parts in the preferred construction that the finger nail or tool may be so pushed in the space 20, that the cap will be forced off 105 without pulling. This makes it more easy to be moved with the nail and without 110

danger of splitting the finger or thumb nail.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A tobacco pipe, comprising a chambered bowl and a stem provided with a draft passage therethrough extending to the exterior of said bowl, and yieldable means closing said passage at the exterior of said bowl.

2. A tobacco pipe, comprising a chambered bowl and a stem provided with a draft passage therethrough extending to the exterior of said bowl, a cup-shaped member inserted into said bowl at the end of said passage, a cap frictionally insertable into said cup-shaped member to form a closure therefor, and a compressible gasket between said cup-shaped member and cap.

3. A tobacco pipe having a bowl and a stem provided with a passage extending through the stem to the exterior of said bowl, a member inserted in said bowl at the end of said passage and having a bore in line therewith, a removable cap frictionally slideable into the end of said member to form a closure therefor, a disk movably held in said cap, and resilient means between said disk and cap to press the disk against the bore through said member.

4. A tobacco pipe, comprising a chambered bowl and a stem provided with a draft passage therethrough, a metal member inserted into the end of said passage and comprising a rim portion, a bored hub and a web connecting said hub and web connecting said hub and rim, and a cap having a neck portion frictionally insertable into said member between the inner wall of the rim

and the outer wall of the hub, a gasket movably held in said neck, and a spring between said gasket and cap to press said gasket against the end of said hub to seal passage therethrough.

5. A tobacco pipe, comprising a chambered bowl and a stem provided with a draft passage therethrough extending to the exterior of the bowl, a cup-shaped member inserted into said bowl at the end of said passage, and comprising an annular rim portion having an outwardly directed end flange at one side, a web across the other side, a hub at the center of said web transverse thereto and having a tapered exterior surface, and a cap having a chamber therein from one end to form a neck portion to frictionally engage the inner surface of said rim, the free end of said neck portion adapted to encircle said tapered hub, a compressible gasket within the chamber of the cap, a spring in said chamber and bearing on said gasket to press it against the bore through said hub, the outer end of said cup-shaped member having slits therethrough so as to render it radially expansible thereat.

6. A tobacco pipe comprising a chambered bowl and a stem provided with a draft passage therethrough extending to the exterior of the bowl, a compressible gasket inserted into said bowl at the end of said passage, and means for holding the gasket in place in the passage.

7. A tobacco pipe comprising a chambered bowl and a stem provided with a draft passage therethrough extending to the exterior of the bowl, a compressible gasket inserted into said bowl at the end of said passage, and yielding means for holding the gasket in place in the passage.

In testimony whereof, I have hereunto signed my name in the presence of two subscribing witnesses.

JOHN BACHMANN.
